UNITED STATES PATENT OFFICE.

ROY F. FULLINGTON, OF CLIFTON HILL, MISSOURI.

INCUBATOR ATTACHMENT.

1,205,445.

Specification of Letters Patent.

Patented Nov. 21, 1916.

Application filed September 18, 1914. Serial No. 862,376.

To all whom it may concern:

Be it known that I, ROY F. FULLINGTON, citizen of the United States, residing at Clifton Hill, in the county of Randolph and State of Missouri, have invented certain new and useful Improvements in Incubator Attachments, of which the following is a specification.

This invention relates to incubators or brooders, and has particular reference to an attachment for that type of devices which may be depended upon to automatically regulate the temperature at which the brooder or incubator is to be kept.

More specifically, it is an object of this invention to provide means normally quiescent for removing heated air from the interior of the incubator when actuated automatically by means governed by the increase of heat, so that overheating of the incubator is prevented.

A further object is to adapt the means previously set forth to prevent the under cooling of the incubator and to further provide means so simple in their construction and so capable of being cheaply manufactured that costly thermometers or thermostats may be dispensed with and yet their necessary operations performed in an equally efficient manner.

The above and additional objects which will become apparent as this explanatory description proceeds, are accomplished by such means as are illustrated in the accompanying drawings, described in the following specification, and then more particularly pointed out in the claims which are appended hereto and form a part of this application.

With reference to the drawings, wherein there is illustrated the preferred embodiment of this invention as it is reduced to practice, and throughout the several views of which like characters of reference designate similar parts: Figure 1 is a plan view of an incubator with the cover and the egg trays removed, showing the various attachments comprehended by this invention as properly positioned, Fig. 2 is a sectional view through the air supply and removing means, Fig. 3 is a perspective view of the fan casing, and Fig. 4 is a view showing in detail the operation of the thermostat replacing means, or the automatic regulator. Fig. 5 is a detail sectional view on the line 5—5 of Fig. 1.

With reference to the drawings the nu-

meral 5 denotes the inclosing body portion of an incubator or brooder which may be supported in any usual manner as indicated at 6 and which is provided with a hinged closure 7, here illustrated as in its outwardly swung position. The interior of the casing 5 is adapted to be filled with rows or tiers of egg trays, which may be of the usual construction positioned in the customary manner. It is purposed by this invention to provide an electric fan 8 which shall be intermittently actuated as the amount of heat entering into the incubator shall dictate in order to maintain a proper temperature within the incubator. The electric fan is positioned in an auxiliary casing 9 and includes a small motor 10 to the central shaft of which is attached a fan 11 surrounded by a fan casing 12. Suitable sources of a difference of potential such as 13 are provided to furnish the motive power to the motor 10 being connected directly thereto in one instance by the wire 14 and indirectly in the other instance as shall be hereinafter more fully described.

Secured to the inner wall of the incubator 5 immediately adjacent one end of the outer casing 9 is a longitudinally extending air pan 15 which is apertured along its bottom as at 16 for communication with the interior of the incubator.

A pair of air circulating pipes 17 and 18 are longitudinally positioned within the pan 15 and pass outwardly therefrom through the wall 5 of the incubator at a convenient point to enter the fan chamber 9. Through one of these pipes 17 warm foul air passes from the incubator and escapes through an opening 17^a in the pipe 17 into the fan chamber 9 or by a branch pipe outside the machine. An inclined partition 17^b is placed in the pipe 17 and divides the same just behind the opening 17^a so as to direct the path of air to the opening. The pipe 17 for convenience is continued rearwardly a short distance and then turned to connect with the eye of the fan 12. A branch pipe 20 extends from the turn of the pipe 17 and passes through the wall of the fan chamber 9, opens into the air without and thus provides means whereby fresh air enters the fan when the latter is running, said air being forced through the pipe 18 into the incubator. A conical cap 19 depends from the inner end of the pipe 17 directly above the tray 15 for the purpose of forming a broad

opening or inlet by which air may be directed into the pipe.

The automatic regulating means whereby the operation of a fan may be controlled to maintain a practically constant temperature in the incubator is illustrated more particularly in Fig. 4. In this figure, the numeral 21 designates a heater formed of a number of heating chambers, one of which 5 22 is adapted to contain the heating element 23 which as here shown may be a lamp, although it is obvious that any other means such as gas or electricity could be employed with equal facility for this purpose. The 10 heating chamber 22 is apertured as at 24 in order to permit the damper 25 to be loosely dependent therein, such damper being carried at the end of a movable rod 26 which is secured to a support 27 which may be one 15 of the egg trays if so desired in any suitable pivotal manner, although a specific description of a simple and novel means will be here afforded. The rod 26 may be formed with an eye 28 at its supported end, the said 20 eye being embraced by a staple or other fastening means 29 so that the eye is maintained in a vertical plane and free to rotate slightly therein upon the obvious rounded portion, although frictionally resisting such 25 rotation sufficiently to normally support the light damper 25 in a manner very sensitive to varying degrees of surrounding pressure.

A support 30 provided with securing extensions 31 is suitably mounted in the interior of the incubator in the most convenient position where it will be readily accessible and yet not occupy space desired for other purposes. One of the extensions 31 is provided with a threaded aperture to receive the stem 32 of an adjusting means 33, the upper end of which bears a rubber washer 34 or other suitable insulation. At 35 and 36 respectively there are pivoted a pair of 40 arms 37 and 38 the former carrying a weight 39 at one end, in order to normally depress the latter while the arm 38 is formed with an enlarged contact portion 40 and is adapted to be adjustably supported by the screw 45 33. Flexible connections 41 are suitably interposed between the damper arm 26 and the free extremity of the weighted arm 37, so that depression of the damper arm will loosen or cause a slack in the connection 50 41 to permit the weight 39 to remove the weighted end of the arm 37 from the vicinity of the enlarged contact 40 while conversely elevation of the damper 25 would immediately insure a contact between the 55 adjacent extremities of the arms 37 and 38. Suitable leads 42 connect the source of difference of potential 13 directly with the arm 37 while a similar wire 43 operatively connects the arm 38 with the remaining point 60 65 of contact on the electric fan 8 so that a cir-

cuit is completed upon the contacting of the levers 37 and 38.

An increase of heat generated by the element 23 might very easily prove detrimental to the contents of the incubator, yet before 70 such heat could do harm in the presence of this invention the damper 25 would necessarily be buoyed up causing a contact between the pivoted arms and a completion of 75 the circuit through the fan, which would then be actuated to force cool air into the casing through pipe 18 and drive out the foul air through the pipe 17. On the other hand should the temperature of the incubator become too low, it will be seen that the 80 cause for this will be the failure of the heat generated by the lamp 23 from exerting any buoyant effect upon the damper 25, which as explained will cause a slackening in the connections 41, so that the connection will be 85 broken between the pivoted arms and the heat again free to raise the temperature of the incubator without being disturbed or lessened by the rotation of the fan. It will thus be seen that efficient means have been 90 provided capable of replacing the usual costly thermostat while at the same time forming a reliable automatic regulator for the heating of an incubator or brooder thereby attaining the previously presented objects. 95

While in the foregoing however, there has thus been illustrated in the drawings and described in the specification, such combination and arrangement of elements as constitute the preferred embodiment of this invention, it is desired to emphasize the fact that such minor changes in the matters of proportion and degree may be made in later adaptations of this device as shall not alter the spirit of the invention as defined in the 100 appended claims.

What is claimed is:

1. An incubator attachment including an exhaust pipe for the air of said incubator, an inlet pipe therefor, a fan for circulating 110 air through both of said pipes, a heating element for said incubator, means sensitive to the amount of heat generated by said element, adjustable means for controlling the automatic operation of said sensitive means 115 in regulating the amount of heat distributed, and means connected with said adjustable means and interconnected with said fan to cause actuation of the latter upon an increase of heat beyond said maximum. 120

2. In combination, with a heating element, a damper mounted in the path of the heated gases generated by said element and adapted to be actuated by the flow of such heated gases, a pair of pivoted arms, means for adjusting one of said arms, means carried by the other of said arms and tending to prevent contact of the two, connections between said damper and said second arm to cause a contact of said arms upon rise of said 125 130

damper, an air pan apertured longitudinally, an outlet pipe spaced from said air pan to draw heated air therefrom, an inlet pipe positioned in said pan to convey a 5 cooler air, and fan means for circulating air through said inlet and outlet pipes in a circuit set in motion by the contact between said arms caused by said damper.

3. The combination with an apertured 10 tray, of a pipe serving as an air outlet from said tray, an air inlet for said tray, a fan for circulating air through both of said pipes simultaneously to cool the tray, a heating element, a damper sensitively pivoted in 15 the path of the heated gases from said element for actuation by the flow thereof, a support, arms separately pivoted to said support, adjustable means supporting one of

said arms weight means carried by the other of said arms to prevent a contact between the arms, a flexible connection between said weight arm and the sensitive mounting for said damper to cause a contact between the arms upon movement of the damper in one direction and permitting 25 said weight means to break the contact of said arms in the other direction and a circuit closed by contact between said arms for the operation of said fan.

In testimony whereof I affix my signature 30 in presence of two witnesses.

ROY F. FULLINGTON.
